UNITED STATES PATENT OFFICE.

JOHN H. HILTZ AND JOHN B. SMITH, OF DETROIT, MICHIGAN, ASSIGNORS TO CHAMBERLIN METAL WEATHER STRIP COMPANY, OF DETROIT, MICHIGAN.

CASEMENT-WINDOW.

No. 873,045.

Specification of Letters Patent.

Patented Dec. 10, 1907.

Application filed July 6, 1907. Serial No. 382,502.

To all whom it may concern:

Be it known that we, JOHN H. HILTZ and JOHN B. SMITH, citizens of the United States, residing at Detroit, in the county of Wayne 5 and State of Michigan, have invented certain new and useful Improvements in Casement- Windows, of which the following is a specification, reference being had therein to the accompanying drawing.

10 This invention relates to improvements in casement windows and has for its primary object the provision of improved means for sealing the space intermediate the border of the sash and the window casing or frame 15 against the admission of dust, moisture, air etc., and more particularly the space beneath the bottom edge of the sash.

The invention comprehends the provision of a spring metallic weather strip interposed 20 between the lower member of the sash frame and the bottom member of the sash secured at one edge to one of said members and formed to permit the parts to readily ride over each other in the closing or opening 25 movement of the sash and having a projecting ridge near its free edge arranged to spring into and interlock with a grooved portion in the member to which it is unattached.

A convenient embodiment of the invention 30 embraces the provision of a strip of the character described secured at one edge to the stop-strip on the lower member of the frame or casing and having its inner edge free and projected upwardly and inwardly 35 from said stop-strip, and the bottom member of the sash being undercut to ride over and receive said free edge of the strip, the outer surface of said sash member extending downwardly to constitute a flange arranged 40 to abut the outer surface of the stop-strip.

The novel features in the construction and arrangement of the several parts of our structure will be apparent from the detail description hereinafter contained when read in connection with the accompanying drawings 45 forming part hereof.

In the drawings, Figure 1 is a perspective view of one corner of a window casing or frame, and the swinging sash hinged thereto, 50 including the weather strip interposed between the same; Fig. 2 is a transverse sectional view through the frame and sash, the sash being shown in closed position; and Fig. 3 is a sectional view through one of the 55 side members of the frame showing the quan-

ner of undercutting the same for the reception of the strip interlocking member of the sash.

Referring more specifically to the drawings, wherein like reference characters designate corresponding parts in the several views, A designates one of the vertical or side members of the frame or casing, B the lower member thereof, C the side of the swinging sash hinged as at D to the member 60 A, and E the bottom member of said sash. The sides and top (not shown) of the sash are grooved as at F for the reception of the sealing flange G of a weather strip H secured to the face of the member A, this particular 65 strip being of a type well known in this art.

Projecting upwardly from the surface of the frame member B, we provide a stop-strip I having an upwardly opening groove J longitudinally disposed and extending the full 70 length thereof for the reception of a downwardly turned edge K of the spring metal weather strip constituting a characteristic feature of the present improvement. Extending inwardly at right angles to the flange 75 or downwardly turned edge K of the strip, we provide a flat portion L overlying the stop-strip I and rigidly secured thereto by means of tacks M. The strip is scored as at 80 N to constitute a hinge and is projected upwardly and inwardly from the line of scoring a considerable distance to constitute a smooth riding surface O, terminating near the extreme edge of the strip in a longitudinal ridge P for a purpose as will presently appear, the edge Q of the strip receding from the ridge P at a gradual inclination and being turned under at its extreme edge to render the same smooth as at R.

I undercut the bottom surface of the lower 90 member E of the sash, as at S, to provide a depending portion or flange T arranged to abut the outer surface of the stop-strip I and also to provide a groove U for the reception of the ridge P of the spring metal strip. The 95 formation of this groove U and the adjoining surfaces of the undercut portion of the member E is complementary to the contour of the weather strip whereby to snugly fit or interlock therewith when the sash is closed, as 100 may be clearly seen from Fig. 2. The groove U in the present instance is formed in the under surface of a piece of molding secured to and constituting a part of the lower member 105 E of the swinging sash, the edge W of 110

- this molding extending downwardly somewhat at a gradual inclination similar to the inclination of the surface Q of the strip, whereby to permit said edge to freely ride 5 over the portion O of the strip and depress the free edge of the strip in the closing movement of the sash and similarly over the ridge P thereof in the opening movement of the sash.
- 10 The lower end of the side member A of the window frame or casing is undercut as at Y for the reception of the end of the weather strip and also to accommodate the end of the molding V.
- 15 By the arrangement of the parts as hereinabove described, we provide a highly efficient, simple, and durable sealing engagement between the lower member of the window frame or casing and the bottom 20 member of the swinging sash; and an engagement which, though securely interlocking when the sash is closed, at the same time enables a ready opening and closing movement.
- 25 I claim:
1. The combination with a window casing and swinging sash therefor, of a spring metallic weather strip interposed between the bottom members of the sash and frame, said 30 frame having a stop-strip, and said strip be-
- ing secured at one edge to said stop-strip near the upper surface thereof and projecting inwardly and upwardly therefrom to be free at its inner edge and formed to permit the sash to ride thereover in the closing movement of the sash, the sash having a grooved portion in which said free edge may spring and interlock. 35
2. The combination with a window casing and swinging sash therefor, of a spring metallic weather strip interposed between the bottom members of the sash and frame, said frame having a stop-strip, and said strip being secured at one edge to said stop-strip near the upper surface thereof and projecting inwardly and upwardly therefrom to be free 40 at its inner edge and formed to permit the sash to ride thereover in the closing movement of the sash, the sash having a grooved portion into which said free edge may spring 45 and interlock, and a depending portion arranged to abut the outer surface of the stop-strip. 50

In testimony whereof we affix our signatures in presence of two witnesses.

JOHN H. HILTZ.
JOHN B. SMITH.
